UNITED STATES PATENT OFFICE.

ALFRED COTTON, OF NEWARK, NEW JERSEY.

SMOKE-CONSUMING FORCED-DRAFT STEAM-BOILER FURNACE.

No. 907,572.

Specification of Letters Patent.

Patented Dec. 22, 1908.

Application filed March 26, 1906. Serial No. 307,982.

To all whom it may concern:
Be it known that I, ALFRED COTTON, a subject of the King of Great Britain, residing at Newark, in the county of Essex and State of New Jersey, have invented certain new and useful Improvements in Smoke-Consuming Forced-Draft Steam-Boiler Furnaces, of which the following is a specification, reference being had therein to the accompanying drawings, in which—

Figure 1 is a perspective view of the furnace; Fig. 2 a horizontal sectional view on the line II—II of Fig. 3; Fig. 3 a vertical sectional view on the line III—III of Fig. 2; Fig. 4 a transverse vertical sectional view on the line IV—IV of Fig. 2; Fig. 5 a front elevation of a portion of the furnace; Fig. 6 a side elevation of the furnace; Fig. 7 a vertical transverse section on the line VII—VII of Fig. 2; Fig. 8 a detail view of the steam supply valve controlled by the fire door; Fig. 9 a vertical sectional view of the fire door; Fig. 10 a vertical sectional view of the fire door on the line X—X of Fig. 9; Fig. 11 a side elevation of the fire door; Fig. 12 a partial plan view thereof; Fig. 13 a partial front elevation showing the upper end of the fire door; Fig. 14 a vertical sectional view of the controller for the secondary air; Fig. 15 a similar view of the controller taken on a plane at right angles to the plane of Fig. 14; Fig. 16 a plan view of the controller; Fig. 17 an enlarged elevation of the fire bricks through which the steam and air pass into the fire box; Fig. 18 a horizontal sectional view on the line XVIII—XVIII of Fig. 19; and Fig. 19 a vertical sectional view on the line XIX—XIX of Fig. 17.

One of the many objects of this invention is to provide a forced draft furnace which will efficiently burn all descriptions of solid fuel, but which is particularly well adapted to efficiently burn bituminous coal and other smoky fuels with the emission of very little or no smoke.

As is well known, immediately a fresh supply of bituminous coal is thrown upon the fire the distillation of hydrocarbons commences, and if smoke is to be prevented a supply of air must be admitted above or "after" the fire to properly consume these hydrocarbons. Hydrocarbons are also evolved when the fire is broken up from time to time through the fire door.

It is one of the main objects of this invention to provide means whereby, when the

fire door is open for the purpose of either adding a fresh supply of fuel or breaking up the fire, a supply of air, which may be termed secondary air, will be delivered above the fire in such manner and in such controlled quantities that the hydrocarbons will be consumed and smoke prevented.

A further object of the invention is to so construct the furnace that this secondary air will be delivered in such manner as to be most efficient both as to the amount of air, the length of time during which the air is fed to the fire, and as to the direction of the air currents.

There are many other important features of the invention which will be more fully hereinafter described and particularly set forth in the appended claims.

Referring to the various parts by numerals, 1 designates the boiler proper which is supported by the walls of the furnace in the usual, or in any approved manner; and 2 the grate bars which also may be of any desired form. The bridge wall 3 is hollow near its upper end to form the horizontal transverse flue 4, as shown clearly in Figs. 2 and 3. In the side walls of the furnace horizontal flues 5 and 6 are formed, said flues connecting at their rear ends with the ends of the flue 4 formed in the bridge wall; and in the front wall of the furnace is formed a horizontal flue 7 which is connected to the forward end of the flue 5 and extends about half way across the front of the furnace, terminating short of the fire door opening, as shown clearly in Fig. 2. All of these flues are arranged a suitable distance above the grate bars, as shown clearly in Figs. 3 and 4, and the walls of all of said flues are provided with openings which put said flues into communication with the fire box above the grate.

The forward half of the inner wall of the flue 6 is perforated, and the rear half of the inner wall of the flue 5 is likewise perforated, so that the openings in one wall are diagonally opposite those of an opposite wall and directly opposite the solid portion of the wall on the opposite side of the fire box, as shown clearly in Fig. 2. The inner wall of the flue 7 is perforated and that portion of the fire box wall of the flue 4 which is directly opposite flue 7 is not perforated, the other half of said wall being perforated as shown clearly in Fig. 2. The object of so locating these openings is to produce a circular motion of air and hot gas over the fire when air is ad-

mitted into the flues 4, 5, 6 and 7 when the fire door is open as will be more fully herein-after described. It will be readily seen that by this peculiar arrangement of the air jet openings the inflowing air from one set of jets will be diverted by the jets from an adjoining set of openings, and that the result will be a rotary movement of the air over the fire. The rear wall of the bridge wall flue 4 is also perforated to permit air to pass back into the combustion chamber at the rear of said wall. At the rear of these openings is arranged an upward and rearward inclined deflector wall 8 against which the air flowing rearward from the bridge wall flue will impinge and will be spread and directed upward. At the tip of the diverging wall 8 is a flat crown wall 9 over which the gas passes. This crown wall is comparatively narrow and from its rear edge the bed 10 of the combustion chamber inclines downward and rearward to the rear wall of the furnace. One special advantage in providing the crown wall and the downward and rearward inclined part 10 of the combustion bed is to secure a swirling of the gas and air just in the rear of the crown wall. By thus causing eddies in the air at this point it is held back and a more perfect combustion secured, without interfering at all with the draft of the furnace. Connected to the center of the bridge wall flue 4, at the bottom thereof, is a flue 11 into which projects a blower 12, said blower being located in the side wall of the furnace, as shown clearly in Figs. 2 and 7 and through which the supply of secondary air is delivered by a steam jet, said jet being controlled, when the fire door is open, by means of automatic mechanism which is permitted to operate when said door is swung to its open position.

The automatic controlling means for the secondary air supply consists of the steam actuated controller 13 which is connected by suitable pipes to the steam supply, the jet blowers and the valves by means of which the controller is regulated. The controller consists of an upper vertical steam cylinder 14 and a lower water cylinder 15, the two cylinders being connected together and in communication with each other as shown clearly in Figs. 14 and 15. The steam cylinder is provided with a small inlet port 16 at its upper end and with a larger inset port 17 at its lower end. The main steam supply pipe 18 is connected to the port 17 through pipe 19 and to the port 16 through pipe 20, said pipe 20 being connected to pipe 19, as shown clearly in Fig. 6. In the pipe 19 is provided a regulating valve 21 and in the pipe 20 is provided a small valve 22. Valve 22 is open slightly so as to permit steam to slowly leak through pipe 20 into the upper end of the steam cylinder 14 and to thereby gradually equalize the pressure of steam admitted to the lower end of said steam cylinder.

der through pipe 19. By means of the valve 21 the supply of steam to pipe 19 may be regulated, or entirely cut off should occasion require. In the cylinder 14 is mounted a piston 23 which is normally near the bottom of said cylinder but above the port 17, said piston in its normal position closing outlet port 24, as shown clearly in Fig. 14. Connected to the piston 23 is a downward extending piston rod 25 which projects into the cylinder 15 and carries at its lower end a piston 26 which fits the interior of the water cylinder 15. This piston is formed with a port 27 which is closed by a spring pressed valve 28 seating against the under side of said piston, said valve opening downward. The upper and lower ends of this water cylinder are connected by a passage 29 which opens into the cylinder near the ends thereof and above and below the piston 26. The upper end of this passage 29, where it opens into the cylinder, is controlled by an adjustable needle valve 30.

The water cylinder is supplied with water from the condensation in the steam cylinder. When the piston 26 is moved up, as will be hereinafter described, the valve 28 opens downward and permits the water above the piston to pass through the port 27 so that the piston will move upward rapidly. When the piston is again depressed or permitted to return to its normal position the valve 28 closes port 27 and the water below the piston will move slowly through passage 29 to the upper part of the cylinder above the piston 26. The speed of the piston in its downward movement may be readily governed by the adjustment of the needle valve 30.

Connected to the port 24 of the steam cylinder 14 is a steam pipe 31 and this pipe is connected to the steam jet of the blower 12 by means of a pipe 32, and the pipe 20 is connected with valve 33 by a pipe 34. Pipe 31 is connected at its forward end to a steam jet 35 which is arranged to deliver steam into the upper end of a blower 36 which is mounted vertically in the top of the fire-door 37. In the pipe 31 just above the fire-door is arranged a valve 38. On the fire door is secured a valve operating arm 39 which carries at its upper end an adjustable striking-pin 40 which is adapted to engage the stem 41 of the valve 38 when the fire door is closed to force the said valve stem inward and open the valve 38, thereby permitting steam to flow through pipe 31 and jet 35 into the blower 36 when the fire door is closed. The valve 38 is an ordinary self-closing valve which will automatically return to its seat when the fire door is open and the striking pin 40 is moved away from the valve stem. The purpose of this is to prevent steam flowing through the pipe 35 when the fire door is open.

The valve 33 is provided with a stem 42.

which is adapted to be engaged by a pivoted arm 43, said arm being normally drawn toward the valve stem 42 by means of a spring 44. The outer free end of the arm 43 is provided with an adjustable eye-bolt 45 and said eye-bolt is connected to the fire-door by means of a chain 46. From the valve 33 a pipe 47 leads into the ash-pit under the grate bars.

16 The operation of the controller for the secondary air may be briefly described as follows:—In the normal position of the parts, after the fire door has been closed for a considerable period, the piston 23 of the controller covers the port 24 thereby preventing steam passing into the pipe 31. The pressure of steam above and below the piston 23 and in pipe 24 is equal. When the fire door is opened either to permit fresh fuel 20 to be placed on the fire or to break up the fire, valve 38 will be closed immediately by reason of the arm 39 being swung away from said valve. This will prevent steam issuing from the jet 35. As the door swings on its pivot the spring 44 will swing the arm 43 and cause it to force inward the valve stem 42 thereby opening the valve 33 and permitting the steam to escape from pipe 34 through pipe 47 into the ash-pit. This will 25 30 at once exhaust steam from the upper part of the cylinder 14 above the piston therein, and permit the steam below said piston to force it upward. The steam will then pass through port 24 into pipe 31 to the steam-jet blower 12, thereby injecting steam and air into the flue 11 and thence through flues 4, 5, 6, and 7. From these flues the air and steam will pass into the fire-box above the fire as previously described. The steam 40 and air will also pass rearwardly through the bridge wall and against the deflector wall 8 and thence rearward through the combustion chamber as previously described. This will continue as long as the fire-door is open 45 and the valve 33 is held in its open position. Should it be desired to open the fire-door at any time without blowing secondary air over the fire as described, it is simply necessary to hold the arm 43 away from the valve 50 stem 42 while the door is open. The chain 46 will permit this to be done.

When the fire door is closed valve 38 will be at once opened through the arm 39, and striking-pin 40, and steam will issue from 55 the jet 35 and air and steam will pass through the blower 36 into the fire-door and from thence into the fire-box above the fire, as will be more fully hereinafter described. On closing the fire-door the chain 46 will swing 60 arm 43 away from the valve stem 42 and permit valve 33 to automatically close, said valve being an ordinary self-closing valve. As soon as this valve is closed the pressure in the pipe 34 and in the top of the steam cylinder 14 will be gradually raised by rea-

son of the leakage of steam through the valve 22. This gradual raising of the steam pressure in the upper part of the cylinder 14 will gradually depress the piston 23, by reason of the weight of the large piston 26 70 connected to the lower end of the stem 25. This downward movement of the piston 23 will be governed, as hereinbefore described, by the speed of the water moving upward through the passage 29. Steam will continue 75 to flow through pipe 31 to the blowers 36 and 12 until piston 23 is moved to the limit of its downward travel and covers port 24. As soon as it reaches this point steam will be cut off from the blowers 12 and 36 thereby 80 stopping the supply of secondary air. The main supply of air is fed into the ash-pit through the main blower 48 which is supplied with steam through the main supply pipe 49 connected to the pipe 18. The ash- 85 pit is closed in any suitable manner to maintain an air pressure below the grate. Pipe 19 is connected to the blower 12 by means of a pipe 50 in which is arranged a valve 51. By this means the blowers 12 and 48 may be 90 supplied with steam if desired independently of the controller 13. This valve 51 is normally kept closed.

The fire-door is preferably hollow as shown in Figs. 9 and 10 and its inner side 52 is perforated for the passage of steam and air into the fire-box above the grate. Near the vertical edges of the inner plate 52 of the door and near its upper edge is formed a depression, one wall of which is at an angle to the adjacent wall of the fire-door opening. Perforations 55 are formed in this angularly disposed wall of this depression so that steam and air passing through said openings will impinge on the adjacent wall of the fire door 105 opening, as shown clearly in Figs. 9 and 10. The object of this is to bring said air into direct contact with the highly heated plane surface whereby said air will be heated and the consumption of smoke and hydrocarbons 110 assisted.

The perforations through the inner side of the fire door are arranged in horizontal rows and between every other row, on the fire side of the door, is arranged an inward extending horizontal rib 52^a, as shown clearly in Figs. 9 and 10. The walls of the openings adjoining each of said ribs are inclined towards said rib, as shown clearly in Fig. 10, so that air passing through said openings will impinge 120 upon the side of said rib. The object of this is to have the air heated and deflected by these ribs.

To secure the best distribution of air around the fire-box through the openings 125 from the flues 4, 5, 6, and 7, I form said openings by means of fire bricks 56 of peculiar shape. These bricks are shown in detail in Figs. 17, 18 and 19. They are double the height or thickness of the ordinary fire brick, 130

and are under-cut at each end to form the face 57. The upper edges of these faces terminate on inclined lines 58 which meet at the point 59 midway between the ends of the 5 brick at the lower edge thereof. The inner face of the brick 60 is vertical, except, of course, where it is under-cut, and the outer face, that is, that face which is not exposed to the fire, is downwardly and outwardly inclined. In each end of the brick is formed a groove 61 which is at an angle to the horizontal lower edge of the brick, and inclines downward and inward toward the fire box. The 10 grooves in two adjoining bricks form downward and inward inclined cylindrical passages through which the air passes into the fire-box from the flue. The air is directed by these passages on to the plane surfaces 62, and is by them heated and deflected. 15 20 It will be noted that the outlet ends of the passages formed by the groove 61 are within the face of the fire-box wall and that they open into angular recesses formed in said wall the bottom of said recesses being horizontal 25 as shown clearly in Figs. 17 and 19. By this construction the ends of the passages formed by the grooves 61 will be protected and said opening will not be choked by the molten slag and hot cinders and clinkers from the 30 fire-box. The brick 56 is not easily broken as its cross-sectional area is greatest in the middle of its length.

Openings in the furnace wall around the fire box as ordinarily constructed are liable 35 to total or partial closure by a kind of molten slag or clinker which slowly runs down the wall and is cooled by the air issuing from the holes. With my construction such clinker will run down the edges 58 of the brick to the 40 corners 59 and from there will pass down the face of the furnace wall. Should any clinker accumulate at the corners 59 by reason of said clinker being cooled by the inflowing air, it can be easily removed, when the furnace is 45 50 not in operation, without liability of damage to the fire bricks. The inflowing air is not only heated or deflected by the surfaces 62 but will be spread by them also. The result of this is that there is practically a thin sheet 55 or film of air passing into the fire box from these openings.

The air flowing rearward through the bridge wall will be so spread by the deflector wall that a thin film or sheet of air will 60 65 pass over the crown of said deflector wall into the combustion chamber. It is also intended that the ribs on the fire door shall spread the inflowing jets of air in like manner. It will thus be seen that the air will be quickly heated and fed into the fire box and combustion chamber in thin sheets or films so that it will be thoroughly mixed with the heated gases.

In Fig. 15 a spring 75 is shown within the 65 water cylinder above the piston 26. The

purpose of this is to assist in restoring said piston to its normal position when the steam pressure in the cylinder 14 is equalized above and below the piston 23 therein.

From the foregoing it will be readily seen 70 that I provide a furnace having many novel features and many advantages. The peculiar method of causing the inflowing air jets to be given a rotary motion over the fire I consider novel and of great importance. 75 The method of controlling the supply of steam and air, or what I term secondary air, is both novel and efficient.

It will be noted that the fire door is connected to the valve operating arm 43 by 80 means of a chain and that the arm 43 is moved by a spring. The object of this is to avoid a rigid connection between the fire-door and the valve operating arm. The fire-door may be thrown open with any degree of 85 violence without in the least affecting the valve and without any danger of injuring or deranging it. By means of the adjustable eye-bolt 45 the proper adjustment may be obtained to secure the proper movement of 90 the arm 43. I also consider it of great importance to so deliver the secondary air into the fire-box that it will impinge upon a plane surface and be by said surface heated and deflected and spread. The air passing into 95 the fire-box from the flues 4, 5, 6, and 7 is heated by contact with the surface 62; that which passes into the fire-box through the fire-door is heated by contact with the walls of the fire-door opening and with the ribs 100 52; and that passing rearward through the bridge wall is heated and deflected by contact with the deflector wall 8.

I have found that when steam is injected directly into the fire-box, either alone or introducing secondary air, the effect is often to agglomerate the carbon particles in soot-flakes which are not so visible as smoke, but which are more objectionable, and the general result is not so efficient as when the steam and air are thoroughly mixed before being injected into the furnace-chamber. It will be seen that thorough mixture of the steam and air is effected in my flues before it reaches the discharge orifices. Further, 115 with my arrangement of flues it is only necessary to use two nozzles—one for each blower. In some cases only one of these blowers may be necessary with one nozzle, though multiple-jet blowers may be used. 120 With steam-jets which blow directly into the furnace it is generally necessary to have a large number of nozzles which either use much steam or are of small bore and choke easily. Also they are usually necessarily 125 placed in inaccessible positions. Any excessive quantity of steam injected into the furnace chamber necessarily reduces the temperature of the gases, and it is therefore advisable that the blowers used for this purpose 130

be highly efficient so that the minimum of steam will be used. This is another reason why I prefer to use a blower or blowers to discharge air into the passages or flues as described, for in this way the blower may more easily be made of correct design and may be placed in such a position as to be very easy of access.

Having thus described my invention, what I claim as new and desire to secure by Letters Patent, is:—

1. A furnace provided with a fire box, a grate therein, means for delivering air to the fire-box above the grate, means for controlling the delivery of said air, said controlling means consisting of a steam cylinder having an outlet port between its ends, a piston therein, a steam supply pipe connected to said cylinder near its ends, means to normally hold said piston at one end of its stroke when the steam pressure therein is equalized on both sides of said piston, the outlet port from said cylinder being closed by the piston in its normal position, a steam jet blower connected to the outlet from said steam cylinder, and means whereby the opening of the fire door will permit the steam to be exhausted from one end of the steam cylinder whereby the piston therein will move toward said exhausted end and uncover the outlet port to permit steam to flow to the jet blower, and means whereby when the fire door is closed the steam pressure on both sides of the piston in the steam cylinder will be slowly equalized and the supply of steam to the jet blower interrupted after a predetermined time.

2. A controller for a steam jet blower comprising a steam cylinder, a water cylinder below the steam cylinder, a piston in the steam cylinder, a piston in the water cylinder, a piston-stem connecting said pistons, a valve in the water piston, a steam supply connected to the steam cylinder above and below the piston therein, an outlet from said cylinder normally covered by said piston, means to exhaust the upper end of the steam cylinder, and means to permit the pressure in the steam cylinder to equalize to return the piston therein to its normal position.

3. A controller for a steam jet blower comprising a steam cylinder, a water cylinder below the steam cylinder, a piston in the steam cylinder, a piston in the water cylinder, a piston-stem connecting said pistons, a valve in the water piston, a steam supply connected to the steam cylinder above and below the piston therein, an outlet from said cylinder normally covered by said piston, means to exhaust the upper end of the steam cylinder, means to permit the pressure in the steam cylinder to equalize to return the piston therein to its normal position, and means to regulate the movement of the water in the water cylinder from one side of the water

piston to the other to govern the speed of the piston in the steam cylinder.

4. A furnace provided with a fire box, a grate therein, a fire door, steam jet blowers for supplying secondary air over the fire, a steam actuated controller for regulating the supply of steam to the blowers, an exhaust pipe connected to said steam controller, said exhaust pipe being normally closed, a spring-actuated device for opening said exhaust pipe, a flexible device connected to said spring actuated device and to the fire door whereby said device is free to operate when the door is open.

5. A furnace provided with a fire box, a grate therein, means for delivering air to the fire-box above the grate, means for controlling the delivery of said air, said controlling means consisting of a steam cylinder, a piston therein, a steam supply pipe connected to said cylinder near its ends, means to normally hold said piston at one end of its stroke when the steam pressure therein is equalized on both sides of said piston, the outlet port from said cylinder being closed by the piston in its normal position, a steam jet blower connected to the outlet from said steam cylinder, and means for exhausting the steam from one end of said steam cylinder whereby the piston therein will move toward said exhaust end and uncover the outlet port and permit steam to flow to the blower.

6. A furnace provided with a steam jet blower for delivering air and steam into the fire box, means for controlling the delivery of steam to said blower, said means consisting of a steam cylinder, a piston therein, a steam supply pipe connected to said cylinder near the ends thereof, means to normally hold said piston at one end of its stroke when the steam pressure is equalized on both sides thereof, the steam outlet from said cylinder being closed by the piston in its normal position, means connecting the steam jet blower to the outlet from the steam cylinder, means operated by the opening of the fire door for exhausting steam from one end of said steam cylinder, whereby the piston therein will be moved towards said exhaust end and thereby uncover the outlet port and permit steam to flow to the blower.

7. A furnace provided with a fire box and a fire door, a steam jet blower for delivering air and steam into the fire box, a steam jet blower for delivering air and steam into the fire box through the fire door, means for controlling the delivery of steam to said blowers, said means consisting of a steam cylinder, a piston therein, a steam supply pipe connected to said cylinder near the ends thereof, means to normally hold said piston at one end of its stroke when the steam pressure is equalized on both sides thereof, the steam outlet from said cylinder

being closed by the piston in its normal position, means connecting the two steam jet blowers to the outlet from the steam cylinder, means operated by the opening of the
 5 fire door for exhausting steam from one end of said steam cylinder to permit steam to flow to the blower connected to the fire box, means operated by the closing of the fire door to permit steam to flow from said cylinder to the fire door blower, means operated by the closing of the fire door to close the exhaust from the steam cylinder, and means to permit the steam to equalize on both sides of the piston in the steam cylinder when the
 10 exhaust from said cylinder is closed.

8. A furnace provided with a steam jet blower for delivering air and steam into the fire box, means for controlling the delivery of steam to said blower, said means consisting
 20 of a steam cylinder, a piston therein, a steam supply pipe connected to said cylinder near the ends thereof, means to normally hold said piston at one end of its stroke when the steam pressure is equalized on both sides thereof, the steam outlet from said cylinder being closed by the piston in its normal position, means connecting the steam jet blower to the outlet from the steam cylinder, means operated by the opening of the fire door for
 25 exhausting steam from one end of said steam cylinder, whereby the piston therein will be moved towards said exhaust end and thereby uncover the outlet port and permit steam to flow to the blower, means whereby the closing of the fire door will cut off the exhaust from the steam cylinder, and means to equalize the steam pressure on both sides of the piston in the steam cylinder when the exhaust therefrom is cut off.

40 9. A furnace provided with a steam jet blower for delivering air and steam into the fire box, means for controlling the delivery of steam to said blower, said means consisting of a steam cylinder and a water cylinder, a piston in the steam cylinder, a piston in the water cylinder, a stem connecting said pistons, a steam supply pipe connected to the steam cylinder near the ends thereof, the steam outlet from said cylinder being closed
 45 by said piston in its normal position, means to permit the water on one side of the piston in the water cylinder to pass to the other side thereof when the pistons are moved, a steam jet blower connected to the outlet from the steam cylinder, and means operated by the opening of the fire door for exhausting steam from one end of the steam cylinder to thereby uncover the outlet port from said cylinder.

50 10. A furnace provided with a steam jet blower for delivering air and steam into the fire box, a fire door, a steam jet blower for delivering air and steam into the fire box through said door, means for controlling the delivery of steam to said blowers, said means

consisting of a steam cylinder, a piston therein, a steam supply pipe connected to said cylinder near the ends thereof, the steam outlet from said cylinder being closed by the piston in its normal position, means connecting the steam jet blowers to the outlet from the steam cylinder, means operated by the opening of the fire door for exhausting steam from one end of said steam cylinder, means operated by the fire door to prevent steam passing to the fire door jet blower while the fire door is open, and means operated by the closing of the fire door to permit steam to pass to the fire door jet blower and to close the exhaust from the steam cylinder, and means whereby when said exhaust is closed the pressure on both sides of the piston in the steam cylinder will be equalized.

11. A furnace comprising a fire box, a steam jet blower connected to the fire box, a fire door, a steam jet blower in communication with the fire box through said door, means operated by the opening of the fire door to supply steam to the fire box jet blower while said door is open, means operated by the closing of the fire door to permit steam to flow to the fire door jet blower, means operated by the closing of the fire door to stop the flow of steam to the blowers a predetermined time after the closing of said door.

12. A furnace comprising a fire box, a pair of steam jet blowers, a steam actuated controller governing the supply of steam to said blowers, a fire door, means whereby upon the opening of said fire door steam will be supplied to one of said blowers and will be cut off from the other blower, means whereby upon the closing of said fire door steam will be admitted to the other blower, and means whereby steam will be automatically cut off from both of said blowers a predetermined time after the closing of said door.

13. A furnace provided with a fire box, a steam jet blower for delivering steam and air into said fire box, a fire door, a steam actuated controller containing a balanced steam actuated piston, means whereby the opening of the fire door will exhaust steam from one side of said balanced piston and permit the piston to be moved towards said exhausted side, means connecting the steam jet blower with the controller whereby steam will be supplied to the blower when the balanced piston has been moved from its normal position by the opening of the fire door, means whereby the pressure on the balanced piston of the controller will be equalized when the fire door is closed, and means connected to said balanced piston to permit it to be slowly returned to its normal position to cut off the steam supply to the steam jet blower.

14. A controller for a steam jet blower comprising a steam cylinder, a water cylinder below the steam cylinder, a piston in the

steam cylinder, a piston in the water cylinder, a piston stem connecting said pistons, a valve in the water piston, a steam supply connected to the steam cylinder near the 5 ends thereof, an outlet from said cylinder normally covered by said piston, a steam jet blower connected to the outlet from said cylinder, a fire door, means operated by the opening of the fire door to exhaust steam 10 from the upper part of the steam cylinder, said means cutting off said exhaust when the fire door is closed, and means to permit the pressure in the steam cylinder to equalize to return the piston therein to its normal position when the fire door is closed.

15. A forced-draft apparatus comprising a pair of steam jet blowers, a steam actuated controller governing the supply of steam to said blowers, means adapted to be operated by the opening of a furnace fire door to supply steam to one of said blowers and to prevent steam reaching the other blower, and means adapted to be operated by the closing of the fire door to open the steam sup-

ply to the other blower, and means whereby steam will be automatically cut off from both of said blowers a predetermined time after the closing of the fire door.

16. A furnace comprising a fire box, a steam jet blower, a steam actuated controller governing a supply of steam to said blower, a fire door, means whereby upon the opening of said fire door an exhaust valve will be opened and the steam controller will be moved to place the steam supply in communication with the blower, means whereby upon the closing of said fire door said exhaust valve will be closed and the controller will be gradually returned to its normal position.

In testimony whereof I hereunto affix my signature in the presence of two witnesses this 24 day of March, 1906.

ALFRED COTTON.
